CLAIM

I claim the ornamental design for an herbal filled calming collar for pets, as shown and described.

DESCRIPTION

FIG. 1 is a perspective view of an herbal filled calming collar for pets, showing my new design;

FIG. 2 is a front elevational view of the invention;

FIG. 3 is a rear elevational view of the invention;

FIG. 4 is a left-side elevational view of the invention;

FIG. 5 is a right-side elevational view of the invention; and,

FIG. 6 is a top plan view of the invention, the bottom plan view being a mirror image.
